ICE CUBING MACHINE

James F. Turner and Christian P. Breidenbaugh,
Baltimore, Md., assignors to Flynn & Emrich
Company, Baltimore, Md., a corporation of
Maryland

Application July 8, 1937, Serial No. 152,500

21 Claims. (Cl. 143—38)

The present application is in part a continuation of our co-pending application, Serial No. 85,136, filed June 13, 1936.

The invention relates to a machine which is primarily adapted for producing ice cubes or other small flat-faced blocks adapted for the same purpose as the ice cubes which are made in domestic refrigerators, and while the size of the blocks is not the essential element, the tendency would be to make them of approximately the size of the cubes produced in domestic refrigerators and to make them cubical. By these machines, the small blocks of ice referred to as "cubes" are produced by cutting relatively large cakes of ice, and while the primary object of the invention is the construction of an ice-cubing machine, the machine as a whole and various features thereof are adapted to cutting cubes or other flat blocks of other materials.

While the present machine embodies certain features of the previous application, it includes important novel features of invention not contained in the previous application above cited. The machine of the present application, in addition to other important advantages, is a relatively simple type of machine adapted for quick production on a more satisfactory commercial basis.

Both machines are provided with a reciprocating carriage which, in the preferred form shown in both applications, moves on a substantially upright path, the carriage in both instances being provided with a turn-table or rocking carrier for the ice cake or other material to be cut, which turn-table or rocking carrier is turned near each end of the stroke of the carriage, through an arc of 90 degrees, providing for the scoring of cubical blocks or for scoring at any other suitable angle by slight change if other shapes are to be cut.

The scoring is performed by a gang of scoring saws which project into the path of the cake intermediately of said path, and the severing of the cubes from the cake is performed by a cut-off saw at right angles to the scoring saws and in a plane parallel to the path of the cake at the upper end of its path.

The cake is fed in the direction of the axis of the rocking carrier or turn-table which is at right angles to its path of reciprocation so that after each cut by the cut-off saw the cake moves forwardly. This feed is controlled in both machines by the spacing or off-setting of the respective saw tables or guides. These comprise first the cut-off saw table which surrounds the cut-off

saw substantially in the plane of the saw. This table is slotted or apertured to admit the narrow width of the cake, which is oblong in its transverse cross section. In the machine shown, the cut-off is accomplished on the up-stroke as the cake enters the slot in the cut-off saw table, and the cake, being turned at the top of the stroke, is supported on the cut-off saw table, its length spanning the slot as it moves downwardly after cutting off and turning.

In combination with the cut-off saw table, the machine includes a scoring saw table which is spaced forwardly in the direction of feed beyond the cut-off saw table by a distance equal to the thickness of the cubes and arranged in a parallel plane thereto. As the cake moves downwardly after turning at the upper end of the stroke and passes the lower edge of the cut-off saw table, it advances by a distance equal to the off-set of the tables and to the corresponding dimension referred to as the thickness of the cubes. This scoring table is to best advantage so related to the scoring saws that scoring takes place to a depth exactly equal to the advance of the cake. The cake is thus scored parallel to its short dimension as it moves downwardly and, being turned at the bottom of its stroke, still in contact with the scoring saw table, again moves upwardly and is scored at right angles to the first scoring. At this time the long dimension of the cake is disposed in the direction of the reciprocation and the cake moves upwardly into the slot in the cut-off saw table, the scored portion being thus severed from the cake by the cut-off saw.

These features are in both machines, but the machine of the present application is preferably arranged with the path of reciprocation inclined to the vertical (shown as at 60°) so that the feed of the cake transverse to the path of reciprocation may be accomplished by gravity, though other means may be provided.

It is an important feature of both machines that they rest directly on the floor and that the cake is admitted near the bottom of the stroke, so that very little lifting is necessary and the objectionable pit, in which previous ice-cubing machines have been mounted in order to provide an easy feed of the cake from the floor to the machine, is eliminated. Likewise, the use of a platform for this purpose to which the cake must be hoisted, is avoided.

It is a further important feature of the present machine that when a new cake is to be presented to the hopper or turn-table, the carriage may

be lowered below the end of the normal stroke and/or rocked without effort on the part of the operator, bringing the ice carrier or cage into parallelism with the floor, reducing to the minimum the extent to which the cake must be lifted. And when the feeding of the cake to the carrier has been accomplished, the power operation of the machine and the normal reciprocation of the carriage is immediately resumed.

In order to provide for this additional motion of the carriage, the turning means has been modified and the hydraulic motor, which is the preferred power-operating device, has also been modified to provide for this operation in the most satisfactory manner.

It is also an advantage that the improved machine is operated from a single source of power most conveniently in the form of an electric motor which operates both the scoring and cut-off saws, turns the carrier or cage, and applies pressure to the hydraulic fluid which, in the preferred form of the invention, is oil that is maintained in continuous circulation during the operation of the machine.

It is also a feature of the improved machine that, while the motion may be instantaneously reversed at the top of the stroke, the action of gravity being relied upon to check the upward motion of the carriage and assist in reversing it without shock or undue increase of hydraulic pressure, this shock and increase of pressure are avoided at the bottom of the stroke and the motion of the carriage is initially checked by moving the control valve to a neutral position in which the weight of the carriage and its momentum are relied upon to transfer the hydraulic liquid from one side of the pistons to the other, thus reducing the speed of the carriage, and immediately thereafter the valve is moved to the reversed position in which the fluid is admitted beneath the hydraulic pistons for the upward stroke.

Rocking of the carriage to receiving position at the bottom of the stroke, in the form shown is accomplished by curvature of the carriage guides, and for this purpose the carriage moves below the normal bottom of its stroke. When it is desired to move the carriage and rock it with the carrier to receiving position, a manual control of the hydraulic system is operated as the carriage approaches the bottom of its normal stroke to connect the cylinders on both sides of the pistons so that the downward motion of the carriage at a relatively slow speed is continued, the fluid being transferred due to the weight of the carriage from the lower to the upper side of the pistons until the bottom of the rocking motion is reached and the carriage is in receiving position. When the feeding of the carriage has been accomplished at this low horizontal position of the carrier, the normal circulation is again restored and the carriage moves upwardly and resumes its normal working stroke.

This motion may be accomplished by various mechanisms differing to a greater or less extent from the construction shown, the motion of the carriage and the provision for the admission of the ice at or near the floor level being regarded as an important novel feature of the invention. This is likewise true of the various features and combinations of features herein described and claimed, the angle of feed, the angle of scoring and/or cutting, and the source of power, as well as other features, being subject to change to suit the conditions presented.

In addition to the foregoing, the improved machine includes numerous features and details of novelty which will be brought out in the description of the machine in connection with the drawings.

In the accompanying drawings we have illustrated an ice-cubing machine embodying the features of the invention in the preferred form.

In the drawings:

Figure 1 is a side elevation of the machine.

Figure 2 is a rear elevation taken from the left in Figure 1 and looking in the direction of arrows 2-2, the rear being the direction from which the blocks or cakes are loaded into the hopper.

Figure 3 is a front elevation looking at the machine from the discharge end.

Figure 4 is a fragmentary section on an enlarged scale, taken on the line 4-4 in Figure 2, showing the carriage in elevation near the top of its stroke and moving upwardly in the cut-off operation.

Figure 5 is a section on the line 5-5 in Figure 1 on the same scale, looking downwardly at an incline; i. e., in the direction of the arrow 5-a and showing the carriage in plan.

Figure 6 is a section on the line 6-6 in Figure 5.

Figure 7 is a detail view of the automatically operated hydraulic valve.

Figure 8 is a detail view of a lock for holding the carriage against displacement, particularly during scoring, the position shown being at the beginning of the upward stroke.

Figure 9 shows the same at the beginning of the downward stroke.

Referring to the drawings by numerals, each of which refers to the same or similar parts in the different figures, the machine comprises two side frames 1 and 2 at the left and right sides of the machine, each of which side frames includes an upright 3 at the front of the machine and parallel inclined ways 4 and 4' at the rear.

The carriage 5, as shown, is provided with lower rollers 6 and 7 at one side and 6' and 7' at the other side which run in the ways 4 and 4' and guide and support the carriage in its reciprocations. The carriage is operated by hydraulic or other fluid pressure cylinders 8 and 8' at the respective sides, which contain the usual hydraulic pistons P (Figure 1) which, in turn, are secured to piston rods 10 and 10' to the ends of which is secured a transverse bar 12 referred to as a "crosshead," it being understood that other means not of the fluid pressure type may be substituted for this reciprocating device. This crosshead 12 is shown in Figure 1 at the end of the down stroke and in broken lines at the top of its stroke. The crosshead 12 is connected to the carriage 5 by means of connecting rods 14 and 14' (see Figure 2) which are pivotally connected to the carriage by wrist pins 15 and 15', which pins serve as the axles or shafts on which the upper follower rollers 6 and 6' of the carriage 5 rotate, the said wrist pins or axles being seated in the frame of the carriage 5. The connecting rods 14 and 14' are secured together by cross rods 14'' to form a connecting rod frame 11; and in the upper part of the path of the crosshead 12 and said connecting rod frame, the connecting rods 14 and 14' and crosshead 12 pass through a slot 16 between the parallel cross bars 17 and 17' which connect the said frame members at the top, the connecting rods 14 and 14' being, at the upper end of the stroke, guided and

supported free of the stationary portions of the frame by the connecting rod guiding and supporting rollers 18 which are suitably mounted on brackets on said members 17 and 17'.

In the present instance, the carriage is mounted to reciprocate in a direction inclined to the vertical so that the hopper or cage is also inclined downwardly and forwardly in the direction of feed; i. e., to the right in Figure 1 at a complementary angle to provide for gravity feeding; but it is obvious that the path of reciprocation may be changed and a different type of feed employed without departure from the principles of the invention, some of which relate to other features of the machine which may be utilized without regard to the direction of reciprocation or the type of feed, and that the reciprocating device is also capable of wide variation. However, the combinations of features shown and the manner of arranging and combining them as shown are of importance in their contribution to a greatly improved result in the way of convenience, efficiency, and economy of operation.

The ice cage or hopper 20 which contains the ice cake or cakes, or blocks of other material to be cut, is mounted on the carriage 5 by means of turntable 44 and operated thereon in a manner which bears a general resemblance to the corresponding features of the machine of the above-cited application, but including new features and details adapting it to the present improved machine, to be further described. This hopper or cage, as shown, is preferably of elongated rectangular cross section and is shown open at its opposite ends at 22, 23 in directions at right angles to the plane of the ways 4-4'; i. e., it is open at the rear, which is treated as at the left in Figure 1, for the admission of the cake, and at the front, which is the right in Figure 1, for exposure of the cake to the saws for cutting. The axis of the carrier or hopper 20 and the sides 19 and 19', 21 and 21', are also disposed at right angles to the ways 4 and 4', the direction of feed of the cake being likewise at right angles to the plane of said ways; and with the frame inclined as shown in Figure 1 to give gravity feeding, which is preferred on account of the consequent simplicity, said axis and said sides 19, 19' and 21, 21' are inclined downwardly and forwardly; i. e., to the right in Figure 1, and the cake moves downwardly and forwardly in the direction of said axis after each cut-off operation in returning to its initial cutting position, said sides acting as guiding and presenting means for presenting the material to the saws.

With the machine arranged to give an upright, or a substantially upright, path of reciprocation of the carriage as in the present illustration, the cake is introduced near the bottom of the stroke. This provides for an easy loading of the ice without much lifting from the truck or floor; but to bring the hopper substantially to floor level and, further, to eliminate the elevation of the rear end 22 of the carrier or cage, which is due to the incline, it is provided in the preferred form of the invention that the carriage may be moved below the bottom of its normal stroke to receive a new supply of ice, being at this time rocked to bring the hopper to horizontal position whereby the rear open end 22 of the hopper 20 is swung downwardly almost to the floor 20' in Figure 1.

The ways 4-4', when thus arranged, may be inclined to the vertical at an angle of 30 degrees as shown or any suitable angle, said 30 degree

portion being rectilinear and comprising the normal stroke of the carriage. For the purpose in hand, the ways 4-4' below the locus of the normal stroke are curved at 24 substantially about a center near the forward open end 23 of the carrier, the lower portion of the ways 4 and 4' below said curve being to best advantage substantially vertical as at 25 in Figure 1.

In order to positively control the lower limits of the normal stroke, a pivotally mounted stop 26 has been provided. When the carriage is to be moved down to loading position, this stop 26 is rocked out of the way by hand or otherwise and a by-pass valve 27 in the hydraulic system is opened to permit the carriage to move downwardly to loading position. The motion of the carriage and the hopper 20 is controlled by the follower rollers 6 and 7 and 6' and 7' swinging about the curve 24 of the ways 4 and 4' from the inclined rectilinear portion 24' thereof to the vertical portion 25, thus moving the hopper downwardly to a position near the floor and swinging it to horizontal position with its axis parallel to the floor and the opening 22 near the floor. When the valve 27 is closed, the hydraulic system resumes its normal operation to be described and the carriage moves upwardly, the stop 26 being returned to normal operative position by means of a chain or flexible connection 28 (Figure 2) which connects the swinging stop 26 to the carriage 5 and on the first upward stroke swings the stop to the position shown in Figure 1. In this position the stop limits the downward motion of the carriage to the normal rectilinear stroke so that it is not rocked to receiving position except at the will of the operator by the operations described. It may be noted at this point that valve 27 controls a by-pass 27' whereby the hydraulic fluid is permitted to flow from one side of the pistons in the cylinders 8-8' to the other side so that the carriage moves down slowly by gravity when the valve is opened.

In order that the machine may be fully understood, the fluid pressure system employed will be described. In the form of the invention shown, the carriage 5 is reciprocated by the action of hydraulic cylinders 8 and 8'. These are connected at their upper ends to the casing 29 of the hydraulic valve not shown, and referred to for convenience as identical with said casing, by pipes 30, 31 (see Figures 1 and 2), the lower ends of these cylinders being connected to the same valve casing by pipes 33, 34. The valve casing 29 is connected to the pressure side of the pump, which is enclosed in chamber 55, by pipe 29', and the valve has a discharge connection 55' to said chamber outside said pump from which discharge the pump takes its supply. The valve 29 is operated by a valve rod 35 which is shown in Figures 2 and 6 extending across the machine from the casing 29 to the valve lever 36 to which it is pivotally connected at 37. The lever 36 is in turn pivotally mounted on the frame of the machine at 39, Figure 2.

The carrier or hopper 20 carried by turntable 44 as hereinabove described is turned oppositely with said table at each end of the stroke through an angle of 90 degrees or other suitable angle. As the carrier turns it engages and swings the lever 36, reversing the operation of the hydraulic cylinders to give the return stroke.

In the form of the invention shown, this is accomplished by a cam or dog 40 at the upper end of said lever 36 and one or more corresponding cams or dogs 42 and 43 at the lower end of

said lever. The hopper or cage 20 is mounted on turntable 44 which is in turn mounted on carriage 5. This turntable carries at its periphery two reversing cam rollers 45 and 46. The roller 45 at the top of the stroke on the swing of the turntable and near the end of its rotary motion engages the cam 40, moving the lever 36 to operate the valve 29 to reverse the stroke of cross-head 12 etc. and near the end of the down stroke on the opposite swing of the table 44, the same roller 45 engages the cam 43, moving the valve 29 to a neutral position in which the motion of the carriage is checked, the hydraulic fluid being transferred from one side to the other of the piston by the momentum or the weight of the carriage; and, as the turntable 44 with the carrier 20 thereon continues to rotate and the carriage 5 slows down, the roller 46 engages the cam 42, reversing the operation of the hydraulic device and the motion of the carriage. This is the position of the parts shown in Figure 6.

In this way; i. e., by this mechanism, the downward motion of the carriage is checked somewhat gradually without backing up excess pressure and then reversed. This precaution is desirable, as the downward motion of the carriage is assisted by gravity as well as by the momentum of the carriage and its load. At the top of the upper stroke where the motion of the carriage is resisted by gravity, this precaution being regarded as unnecessary, the hydraulic device and carriage are instantly reversed. The tendency to build up hydraulic pressure at the time of reversal and the consequent leakage, being negligible at the end of the up-stroke for the reason stated, is avoided at the end of the down-stroke where it is a matter of importance by the gradual checking of the motion of the carriage which precedes reversal as just described.

The by-pass 27' controlled by valve 27 previously mentioned connects the two sides of the line; i. e., pipes 31 and 33, leading to the top and bottom ends respectively of cylinders 8 and 8'. The opening of the valve 27, as previously described, permits the carriage to move below the bottom of its normal stroke to the loading position, and has an effect similar to that produced by placing the valve 29 in neutral position; i. e., the momentum or weight of the carriage transfers the liquid from one side to the other of the pistons, permitting the carriage to drift downwardly.

During the lower portion of the normal stroke, the cake is supported at the forward open end 23 of the carrier or cage 20 by the scoring saw table 48 (see Figure 1) which, as shown, is curved downwardly at its lower end at 48'. At the upper end of the stroke after the cut-off operation to be described, and throughout the turning at this end of the stroke, the cake is supported at the forward end of the carriage by the cut-off saw table 49, which is off-set to the rear of the scoring saw table 48 by a distance equal to the height of the cubes; i. e., the thickness of the cut-off portion; and it is also of interest as described in connection with the machine of the previous application that the cut-off saw table 49, which may be also referred to as a guide, is slotted at 50 to admit the narrow transverse dimension of the cake which corresponds to the dimension 50' of the hopper or cage 20 as seen in Figure 6. This provides for the admission of the cake to the slot 50 for the cut-off operation, the cut-off saw

51 being in the plane of, or slightly below and forwardly of, the table 49, and for the support of the cake by the table 49 after the cut-off operation and during and after turning, there being, however, some degree of turning before the cut-off is entirely completed.

Thus, after the cut-off operation, the cake being turned with its long dimension transverse to the feed, it spans the slot 50 resting on table 49 at both sides of said slot. When the direction of reciprocation is reversed, the cake moves downwardly supported by the cut-off saw table 49 and as it passes the lower end of table 49 the cake advances by the normal feed, which in this instance is due to gravity, from the plane of the cut-off saw table 49 to the plane of the scoring saw table 48, progressing downwardly into cutting relation with the scoring saws 52 and beyond the same to the point of reversal at the bottom of the stroke, being first scored in the direction of its short transverse dimension 50' as it moves downwardly, turned at the bottom of the stroke, and scored in the direction of its long transverse dimension 51' as it moves upwardly; after which, as previously described, it continues to move upwardly, the scored portion being severed near the upper end of the stroke by the cut-off saw 51. This cycle of operations is repeated with intervals for loading so long as the machine is in operation. At the time of cutting off, the cake still rests on scoring saw table 48.

The machine as shown is driven for all purposes and as to all its various mechanisms from a single source of power preferably in the form of an electric motor 53 (see particularly Figure 1). Mounted on the shaft of this motor 53 is a grooved drum 54 best shown in Figure 3 which also shows that in the form illustrated the belts are tripled to avoid slippage and undue driving strain. In this figure, the motor 53, valve 29, and adjacent parts are covered by a hood 57.

The pump contained in hydraulic chamber 55 is of the rotary type to the shaft 56' of which is secured a pulley 56. This pulley 56 is driven by belts 57 which are passed around the pulley 56 and laid in the corresponding grooves of the drum 54 about which they are also passed. The scoring saw shaft 58 is provided with a drum 59 secured thereto, which is driven by belts 60 from the drum 54, all said drums and pulleys being suitably grooved to carry the type of belt shown. The drum 59 is elongated and also carries the belts 61 which drive the cut-off saw 51, being passed about a drum 62 on the shaft of the saw 51. These belts 61 are also passed over suitable direction-changing or guide pulleys 63 and 64 best shown in Figure 3.

The manner of leading the hydraulic fluid to the cylinders 8-8' from the pump by way of the valve 29 has been described, also the driving of the pump from motor 53. The drive also includes the operation of friction driving rollers 65 and 65' located at the upper end of the machine and adapted to turn the carrier and turn table, in this instance through an angle of 90 degrees at the upper end of the stroke, and corresponding friction rollers 66 and 66' at the lower end of the machine, and adapted to perform a similar operation turning the table in the opposite direction at the lower end of the normal stroke. In the form of the machine shown, the shaft 67 carrying the toothed pinion 68 is driven by means of suitable gearing connected to the pump, which is preferably of the rotary type. This gearing may consist of a helical gear 168

secured to shaft 56' and driving a helical pinion 169 on the shaft 67. The pinion 68 drives a toothed gear 69 which meshes therewith and which is in turn secured to a shaft 70 which extends upwardly to the rear transversely to the path of reciprocation and oppositely in the direction of the feed. This shaft is provided with bevel gears 71 and 72 secured to said shaft. This shaft 70 also carries the driving friction rollers 66 and 66' at the lower end of the machine at the rear and front respectively, being at the right in Figure 2. The bevel gears 71 and 72 mesh with similar gears 73 and 74, which gears are mounted respectively on shafts 75 and 76 which extend upwardly parallel to the direction of reciprocation of the carriage 5, being supported at their upper ends in suitable bearings in brackets 77 and 78 secured to the frame. These brackets also carry the transverse shafts 79 and 79' on which the driving friction rollers 65 and 65' respectively are mounted. Shafts 79 and 79' are spaced apart at their adjacent ends to pass the crosshead 12. These shafts 79 and 79' have secured thereto bevel gears 80 and 81 which mesh with gears 82 and 83 secured to the shafts 75 and 76 whereby the shafts 79 and 79' carrying the rollers 65 and 65' are driven and the driving friction rollers 65 and 65' are driven at equal speeds and in the same direction. It will also be apparent from the connections described that the friction rollers 66 and 66' at the opposite end of the traverse of the carriage are driven at similar speeds and in a direction opposite to the rotation of the rollers 65 and 65'. In the form shown, the rollers 65 and 65' rotate counterclockwise as seen in Figure 2, and the rollers 66 and 66' rotate clockwise as seen in the same figure. In this figure, the rollers 65' and 66' are covered by rollers 65 and 66.

The carriage 5 and the turntable 44, and the cage or hopper 20, are somewhat similar in principle to the machine of the previous application. The portion of the carriage 5 which merely reciprocates in the direction of the stroke and carries the turntable but does not turn therewith at the ends of the stroke, includes a top plate 82 which is shown in plan in Figure 5 and in elevation in Figure 6. This plate 82, as shown, is in the form of a cross having depending flanges at the sides at 83 and 83' to which are secured the side plates 84 and 84' which, as seen in side elevation in Figure 1, are of trapezoidal outline with the short dimension located upwardly in the direction of reciprocation and transverse thereto. These side plates are connected together at the bottom by cross bars 85 and 85' shown in the form of angle irons.

The carriage frame as thus constructed, or in any suitable form (see Figure 6) carries bearing rollers 86 and 86' at the top, the roller 86 being at the rear and 86' at the front, both rollers being carried by a shaft 87 which is suitably mounted in upwardly turned ears 88 at the front and rear ends of the cross-shaped top plate 82 (see Figures 5 and 6). The carriage 5 is also provided at the front and rear bottom corners with two pairs of bearing rollers 89-89' and 90-90' (see Figures 1, 5, and 6), one roller at each said corner. Rollers 86, 89, and 90 rotate in one plane and rollers 86', 89', and 90' rotate in another plane, both planes being parallel to the path of normal reciprocation. The shafts for these rollers, 89, 89' and 90, 90' are mounted in tubes 91a and 91b which are secured at their ends to the ends of the angles or cross bars 85

and 85' extending from front to rear along each bottom corner of the carriage 5. The bearing rollers 86, 89, and 90 engage a grooved bearing ring 91 which is integral with the turntable structure 44 at the rear and the bearing rollers 86', 89', and 90' engage a similar ring 91', integral with the turntable 44, at the front end of the turntable, the planes of said rings 91 and 91' being parallel to the path of normal reciprocation. The rollers 86, 86', 89, 89', 90, 90' support the turntable on the carriage and provide for its rotation thereon for the purpose of turning the hopper and cake.

The ice hopper or carrier 20 is secured in and to the turntable bearing rings 91 and 91' in any suitable manner, as by means of angle brackets 93 at the top rear on each side (see Figure 5) and 94 at the top front on each side, 95 at the bottom rear on each side and 96 at the bottom front on each side, the brackets being bolted in place on the rings 91 and 91' and slotted at 97 to provide for adjustment of the hopper or carrier 20 for the purpose of equalizing the cuts with the spacing of the scoring saws so as to produce as few undersized cubes at the sides of the cake as the dimensions of the cake will permit. The rings are provided with inwardly extending ears or plates 98 to receive and support the brackets 93 and 94, etc.

In order to provide for the turning of the turntable 44 and the carrier or hopper 20 thereon at the respective ends of the stroke, the turntable 44 has secured thereto arcuate friction members or tracks 99' at the front and 99 at the rear. These are closely similar in function to the corresponding friction members of the machine of the copending application, the important distinction being that they are made flat; i. e., they have their friction surfaces parallel to the axis of the turntable to permit the carriage with the turntable and hopper to swing to horizontal position for the loading operation as previously outlined. These tracks are formed on circular arcs about the axis of the turntable and their plane of rotation is parallel to the path of reciprocation.

Each of the arcuate tracks or bands 99 and 99' is composed of two friction paths which, as shown, are in the same cylindrical surface and parallel, but these latter are off-set in the direction of their lengths at the ends to provide a differently located arc of engagement of said paths by the rollers at the top and bottom, whereby the driving friction rollers 65 and 65', 66 and 66', are permitted to rotate free of engagement with these tracks 99 and 99' during the slight dwell at the ends of the stroke after rotation of the carriage is completed, which prevents burning of the rollers and loss of power by friction after the rotation of the turntable is completed. This is of particular importance when the carriage is stopped by action of valve 27 without removing stop 26, as for inspection. While this construction is capable of change and variation, the arrangement shown is found most satisfactory for the purposes stated. The track 99' is shown in detail in Figure 4, the track 99 being similar (see Figure 5).

The driving friction roller 66' at the lower end of the machine in Figure 1—the operation of roller 66 being similar in connection with track 99—engages the forward or right-hand path 100 (Figure 4) of the track 99', which path, as shown, is provided at its lower end in Figure 4 with an anti-friction roller 101 which is engaged by the friction driving roller 66' at the end of the

swing of the turntable which takes place at the bottom of the stroke, the friction path 100 having passed from contact with roller 66'. This leaves the carriage 5 and the parts thereof free to swing downwardly to the horizontal position of the hopper or carrier 20 when moved to loading position below the end of the normal stroke at the will of the operator as previously described.

As will be noted, the end of the friction path 102, which is engaged by the driving friction roller 65' at the top position of the carriage to rotate the turntable to position in which the long transverse dimension 51' of the cake is at right angles to the path of reciprocation, extends downwardly in Figure 4 at 103 beyond the end 15 of the path 100 and the roller 101, whereby the paths are offset in the direction of their length. The offset provides for the initial engagement of the roller 65' with the path 102 of the track 99' at the top of the stroke and for the release 20 or disengagement of the friction driving roller 66' at the bottom of the stroke after rotation of the turntable and prior to the upward motion of the carriage. The opposite end of the track 99' and both ends of the track 99 are similarly arranged, the operation being similar, except that there are only two of the rollers 101 and these are at the ends of the paths engaged by 25 rollers 66 and 66' when turning is completed at the bottom of the normal path of reciprocation.

The turntable, particularly the hopper or carrier 20, is positioned after each swing by stops 104 and 105 (see Figure 6) which are supported on the frame of the carriage and adjustably mounted, as by means of screws 104' and 105'. The stop 104 engages the outside of wall 19' of the hopper 20 and positions the same with the long dimension 51' of the cross section of said hopper parallel to the direction of reciprocation, the short dimension being at right angles 40 thereto; and the stop 105 positions the carrier or hopper 20 with the long dimension 51' at right angles to the direction of reciprocation.

In order to prevent displacement of the carrier or hopper during cutting, the machine, as shown, is further provided with a locking plate 107 shown in detail in Figures 8 and 9 in its cooperative relation to and with the hopper. This plate is pivotally mounted on the carriage 5 at 109 and provided with follower means 110 whereby it engages a cam track 111 on the frame 50 of the machine at the side.

Figures 5 and 6 show an angle iron 113 which extends across the turntable at the side of the hopper and parallel to the side 19; i. e., from the rear to the front in the direction in which the ice cake is fed through the hopper toward the saws which is also parallel to the axis of the turntable. This angle iron 113 is engaged by the locking surface 108 of the plate 107 to hold the hopper in contact with the stop 104 on the up-stroke when the long dimension 51' of the cross section of the cake and the hopper is parallel to the direction of reciprocation; and, the turntable and hopper being turned at the top of the stroke, the locking surface 112 engages the long side 19' of the hopper near the corner of the hopper on the down stroke to hold the hopper in contact with the stop 105 (see Figure 6), with the long dimension 51' 70 transverse to the direction of reciprocation.

It will be noted that the cam track 111 is curved at the ends 111' and 111'' for convenient engagement with the follower surface 110 of the locking plate 107 as it enters contact therewith,

and that the track 111 extends through an area corresponding to the portion of the path of the carriage between the extreme ends of the normal stroke. The turntable and hopper are thus free to turn at the ends of the stroke and are locked against turning throughout the area in which the ice cake may be engaged by the scoring saws 52 and while it is entering slot 50 in the table 49.

The object in both locking positions is to prevent rocking of the hopper and turntable during reciprocation and particularly while the scoring saws are passing through the cake, thus eliminating any tendency to deflect the saws and injure them or to score at varying angles. The locking device on the up-stroke also causes the cake to register accurately with and enter the slot 50 in the cut-off saw table 49.

While the operation of the machine has been disclosed in connection with the description of the various mechanisms, it may be desirable to consider this operation as a whole.

The initial step in the operation of the machine in the preferred form as shown—the motor 53 having been placed in circuit—is to move the carriage to loading position by rocking the hopper to bring its feeding axis to horizontal position whereby the mouth of the hopper 22 (see Figure 5) is lowered and the hopper is moved downwardly to a position closely adjacent the floor so that but slight lifting of the ice cake is necessary to load it into the hopper. If the ice is carried on a low hand truck, it may be passed horizontally directly into the hopper.

For this purpose, the stop 26, which would otherwise arrest the motion of the carriage at the end of the normal downward stroke, is swung downwardly and rearwardly; i. e., to the left in Figure 1 out of the path of the carriage, and the valve lever 27 is moved to open the by-pass so that the two ends of the hydraulic cylinders 8 and 8' are connected together and the weight of the carriage serves to transfer the liquid from the lower to the upper sides of the pistons.

As the carriage drifts downwardly, the follower rollers 6-6', 7-7' move along the tracks 4 and 4', passing around the curve 24 from the inclined portion of these tracks to the vertical portion thereof at 25 (see Figure 1), whereby the carriage and the turntable and the hopper or carrier 20 are rocked to a position in which the long fore and aft dimension of the hopper, parallel to the axis of the turntable and parallel to the direction in which the ice is fed to the saws and transverse to the direction of reciprocation, is horizontal. The carriage then drifts on downwardly to a position in which the friction bearing rollers 89, 89' and 90, 90' are substantially in contact with the floor, the bottom wall of the hopper being not only horizontal but located immediately adjacent the floor, these parts being indicated in this position in dotted lines in Figure 1. It will be understood that in the arrangement shown, which is subject to variation, the carriage 5, after turning to the horizontal position of the hopper, moves downwardly a considerable distance to its bottom position. The angle of the carriage in loading position is also subject to variation.

The hopper having been loaded, and the cake or cakes advanced therein into contact with the end of the scoring saw table at 48', the valve 27 is closed and the carriage moves upwardly by virtue of the operation of the hydraulic cylinders

to its normal path of reciprocation. At this time, the long dimension 51' of the cross section of the hopper is disposed in the direction of reciprocation. As the rollers 6—6', 7—7' pass the curve 24 of the tracks 4—4', the carriage assumes its normal alignment with the axis of the hopper and turntable, at right angles to the direction of normal reciprocation, which is represented by the portion of the tracks 4—4' above the curve 24 and shown as at an angle of 30 degrees with the vertical; the axis of the carriage, the length of the hopper, and the direction of feed being correspondingly inclined to the horizontal downwardly and to the right in Figure 1, which has been referred to as forwardly because it represents the direction of feed of the cake to the saws after each cut-off operation.

The stop 26, being connected by chain 28 to the carriage, is drawn upwardly and thrown forwardly to its normal stable position as illustrated in Figure 1, and the normal operation of the machine is thus initiated, and normal reciprocation continued. The next operation is the locking of the turntable by contact of the follower surface 110 of the locking plate 107 with the track 111, whereby the side 19' of the hopper 20 is held in contact with the stop 104 (Figure 6) so that the cake cannot change its alignment with the scoring saws 52. As the carriage moves upwardly, the cake is scored in the direction of its long transverse dimension 51'. It then enters the slot 50 of the cut-off saw table 49, with which slot the stop 104 and the lock 107 hold it in alignment, the cake being in contact with the cut-off saw table 48.

As the cake, also referred to herein as a body of solid material, advances, having been thus scored, a portion corresponding in thickness to the off-set of the plane of the cut-off saw 51 from the table 48 and substantially to the off-set of the tables, is cut by saw 50 from the front end of the cake.

When the cut is completed, or substantially completed, the turntable is unlocked or released, the friction driving rollers 65 and 65' engage the friction tracks 99 and 99', or the corresponding paths thereon indicated at 102 in Figure 4, and the carriage begins to rotate, moving the long dimension 51' of the cross section of the hopper and cake or body of material from the position shown in Figure 6, in which it is parallel to the direction of reciprocation, to the position indicated in dotted lines in the same figure, in which it is at right angles to the direction of reciprocation.

The turntable and hopper in this instance and in the particular construction shown are rotated in a clockwise direction as seen in Fig. 2. Near the end of the arc of rotation, which is 90 degrees in this instance, the roller 45 engages the cam or dog 40 on the lever 36 (see Figures 2 and 6), moving said lever 36 and operating the valve 29 to which said lever is connected by the valve rod 35, reversing the operation of the hydraulic cylinders. The turntable and hopper have been thus rotated to a position in which the long dimension 51' of the cross section of the hopper and the ice cake are transverse to the direction of reciprocation, so that the cake spans the slot 50 in the cut-off saw table 49. The cake, on reversal of the carriage motion, moves downwardly past the lower end of the cut-off saw table 49, passing the off-set 49' (Figure 6) which permits the cake to be advanced. In this

instance; i. e., in the preferred form of machine shown, the feed is by gravity, the ways 4—4' being inclined for this purpose, which gives a corresponding incline to the turntable axis and direction of feed and provides for the gravity feed.

The off-set mentioned is substantially equal to the height or thickness of the slice cut by the cut-off saw, and hence of the cubes cut, and represents the distance between the parallel planes of tables 49 and 48, the latter being forward in the direction of feed.

The turntable and hopper having been again locked by the action of the plate 107 and cam track 111, this time in the manner illustrated in Figure 9, the cake moves into contact with the scoring saws 52 and is scored in a direction at right angles to the long dimension 51' of the cross section of the cake and hopper.

As the carriage approaches the bottom of its stroke, the turntable is unlocked and the tracks 99—99' are engaged by the friction drive rollers 66 and 66' and the turntable 44 and the hopper 20 are rotated counter-clockwise as seen in Fig. 2 to the position illustrated in Figure 2; i. e., with the long dimension 51' of the cross section of the hopper again parallel to the direction of reciprocation. At the end of the down stroke, the roller 45 carried by the turntable engages the cam 43 on the lever 36, moving the valve in the casing 29 to neutral position in which the two ends of the hydraulic cylinders 8 and 8' (see Figure 2) are connected together, so that the motion of the carriage is checked and it moves downwardly due to its weight, transferring the liquid from the bottom end of said cylinders to the top.

When the rotation of the turntable and the hopper is substantially completed, the parts being returned substantially to the position shown in Figure 6, the cam roller 46 engages the cam 42, further moving the lever 36 and changing the valve 29 to a position in which the lower ends of the cylinders are connected to pressure and the upper ends are discharging through the valve 29 into the low pressure side of the chamber 55, whereby the carriage moves upwardly to complete the cycle of operations. The carriage is again locked by the operation of the plate 107 and the cam track 111. The cake then moves upwardly past the scoring saws whereby it is scored in the direction of the long dimension 51 of the cross section of the cake and hopper. Then, moving up further on its traverse, the scored portion is severed by the action of the cut-off saw 51 (see Figure 4), the ice cubes 125 cut from the cake 126 being delivered to the chute 127 whereby they are discharged from the machine. The cycle of operations described is repeated so long as the machine is in operation.

As already pointed out, when the ice in the hopper is sufficiently exhausted, the carriage and hopper may be moved downwardly to loading position as previously described by opening valve 27 and removing stop 26 when a new cake is inserted. The carriage is then returned to its normal reciprocation by closing the valve 27, the stop 26 being automatically returned to operative position so that the operation is immediately resumed and is substantially continuous, the cakes being fed consecutively and all cut into uniform cubes.

It is of interest that at the end of each rotation or oscillation of the carriage the rollers 65—65', 66—66' move on out of contact with the friction

tracks 99—99' so that there is no friction after the turn is completed; and the rollers 101 shown at the end of the friction path 100 in Figure 4 are particularly helpful in preventing friction after the rotation is completed during the dwell or when the carriage is stopped at the bottom of its stroke by opening valve 27. It is also of advantage in permitting free swinging of the carriage, the turntable, and the hopper from the inclined position which they take during normal reciprocation, as represented by the upper portion of the ways 4 and 4' in Figure 1, to the horizontal position which the hopper and other parts take when the follower rollers 6—6', 7—7' pass the curve 24 of said ways in moving downwardly to loading position.

The neutral position of the valve in the chamber 29, which is provided for by the presence of the cam 43 engaged by the roller 45 as the carriage approaches the bottom of the stroke, is of particular advantage on the down stroke in that, by permitting the fluid to be more or less freely passed from the bottom to the top ends of the cylinders, the motion of the carriage is gradually checked without creating excess pressure in the cylinders with consequent tendency to leakage which would result from an instant reversal of the hydraulic motor in opposition to the moment and weight of the carriage as it moves downwardly.

The reciprocating carriage and hopper, moving on an inclined path providing a gravity feed transversely of said path with automatic turning of the hopper at each end of said path, the cut-off and scoring saws being intermediate of said path and having their respective tables parallel to the path of reciprocation and off-set by the thickness of the cut-off, providing a simple, completely automatic machine, are regarded as an important novel combination contributing to a new result in the way of a more simple and efficient machine for this purpose than any previously produced.

In connection with the upright path of reciprocation, the provision for moving the carriage and hopper downwardly to the floor for loading is of importance, and the rocking feature whereby a carriage and its hopper, which reciprocate on an inclined path and feed by gravity at right angles thereto, are rocked to the horizontal position of the hopper and moved downwardly to the floor for loading, is worthy of particular emphasis. The term "inclined path" is not critical, the rocking feature being applicable to machines having the path at various angles.

The machine also contains various other features and combinations of parts which are novel in their association and arrangement and contribute to the practical result obtained. Among others, an important contribution to the economy of production is the arrangement for driving the various mechanisms from a single source of power.

While the machine is particularly adapted to cutting ice cubes and is being produced on a commercial basis for this purpose, it is also adapted to cutting blocks of other materials for other purposes. However, in the interest of brevity the terms "ice" and "cubes" have been used throughout the specification and will be used in the claims as including any substantially rigid material which may be cut into small blocks and any shapes into which it may be cut by the machine described or any modification of this machine.

While the path of the carriage in the form shown is inclined to provide for a gravity feed transversely of the path, the inclination of the

path is not essential to the utility of certain features of the machine which may be applied to a machine having a different arrangement; and the term "upright" as applied to the path of reciprocation is intended to include both the inclined path providing for the gravity feed and the vertical path, the device for moving the carriage below or beyond the end of the normal path of reciprocation to and near the floor level for convenience in loading being applicable in its broad conception to the vertical and even to other types of machine.

We have thus described specifically and in detail an ice cubing machine embodying the features of our invention in order that the manner of constructing, applying, operating, and using the invention may be fully understood; however, the specific terms herein are used in a descriptive rather than in a limiting sense, the scope of the invention being defined in the claims.

What we claim as new and desire to secure by Letters Patent is:

1. In a machine for cutting a body of material into relatively small blocks, a carriage, means for reciprocating the carriage on a pre-determined path, a hopper on said carriage adapted to the feeding of said body transversely to the path of reciprocation, scoring saws and a cut-off saw transverse to each other and parallel to said path, projecting into the path of the body at the forward end of said hopper in the direction of feed, automatic means for turning the hopper about an axis parallel to the direction of feed to provide for scoring on intersecting lines, means for regulating the feeding of the body to score and cut a pre-determined thickness, said machine being adapted to be supported substantially on the floor, and having means at one end of said path and under the control of the operator for moving the carriage and hopper beyond the end of said normal path to a loading position closely adjacent the floor with the path of feed through the carriage substantially horizontal.

2. In a machine for cutting a body of material into relatively small blocks, a carriage, means for reciprocating the carriage on a pre-determined path, a hopper on said carriage adapted to the feeding of said body transversely to the path of reciprocation, scoring saws and a cut-off saw intermediate of said path, projecting into the path of the body at the forward end of said hopper in the direction of feed, automatic means for turning the hopper at each end of the stroke about an axis parallel to the direction of feed to determine the angle of scoring, a locking device for locking the hopper after certain of said turning motions and for maintaining it in locked position for the scoring operation, and means for regulating the feeding of the body to score and cut a pre-determined thickness.

3. In a machine for cutting a body of material into relatively small blocks, a carriage, means for reciprocating the carriage on a pre-determined, substantially upright path, a hopper on the carriage adapted to the feeding of said body transversely of said path, scoring saws and a cut-off saw projecting into the path of the body in said hopper at the forward end of the hopper in the direction of feed and intermediate of said path, automatic means for turning the hopper to provide for cutting intersecting scores prior to cutting off the scored material and means for determining the rate of feed and the thickness of the cut-off, the machine being adapted to stand

substantially on the floor, said normal path of reciprocation terminating above the floor and the machine comprising means under control of the operator for moving the carriage downwardly below the lower end of the normal path of reciprocation substantially to the level of the floor.

4. In a machine for cutting a body of material into relatively small blocks, a carriage, means for reciprocating the carriage on a pre-determined normal path inclined to the vertical, a hopper on the carriage adapted to the feeding of said body transversely of said path, and in a downwardly-inclined direction, scoring saws and a cut-off saw projecting into the path of the body in said hopper at the forward end of the hopper in the direction of feed and intermediate of said path, means for turning the hopper between scoring operations to provide for cutting intersecting scores prior to cutting off the scored material, the machine being adapted to stand on the floor, said normal path of reciprocation terminating above the floor and the machine comprising means under control of the operator for moving the carriage downwardly to a loading position below the lower end of the normal path of reciprocation substantially adjacent the level of the floor with the hopper in substantial parallelism with the floor to facilitate loading.

5. In a machine for cutting a body of material into relatively small blocks, a carriage, means for reciprocating the carriage on a pre-determined substantially upright path, scoring saws and a cut-off saw intermediate of said path, a hopper on the carriage for holding said body and presenting it to the said saws, means for turning the hopper to provide intersecting scores, said reciprocating means comprising a fluid pressure motor of the double action reciprocating type and connections from the motor to the carriage whereby the carriage reciprocates in direct correspondence with the reciprocations of the motor, valve means controlling said motor, means for operating said valve means, reversing the motor at each end of the stroke, and means operative near the end of the down stroke for relieving the pressure within the fluid pressure motor prior to reversal.

6. In a machine for cutting a body of material into relatively small blocks, a carriage, means for reciprocating the same providing a forward and return stroke on a single pre-determined inclined path, a hopper on said carriage adapted to the automatic feeding of the said body downwardly substantially at right angles to said path, scoring saws and a cut-off saw arranged intermediate of said path in cutting relation to the path at the forward end of the hopper, and means for turning the hopper adjacent each end of said path to provide intersecting scores.

7. In a machine for cutting a body of material into relatively small blocks, a carriage, means for reciprocating the same on a pre-determined inclined path, a hopper on said carriage adapted to feed the said body by gravity substantially at right angles to said path, scoring saws and a cut-off saw arranged intermediate of said path transverse to each other and parallel to said path at the forward end of the hopper, means for turning the hopper at each end of said path to provide intersecting scores, a plurality of guiding means for said body forwardly of the hopper and corresponding to the scoring and cut-off saws respectively, said guiding means being parallel to said path and to said cut-off saw

and said guiding means being offset one from the other in the direction of feed by a distance determining the thickness of the cut-off, one said guide being adapted to support said body during 5 scoring and cutting off and the other said guide, which is rearmost as to the direction of feed and substantially in the plane of the cut-off saw, being adapted to support the cake at the upper end of the stroke, after cutting off and prior to 10 the next scoring operation.

8. In a machine for cutting a body of material into relatively small blocks, a carriage, means for reciprocating the same on a pre-determined path of normal reciprocation which is inclined to the 15 vertical, a hopper on said carriage adapted to the feeding of said body by gravity forwardly and downwardly substantially at right angles to said path, scoring saws and a cut-off saw arranged in cutting relation to the path at the forward end of the hopper, means for turning the hopper to provide intersecting scores, a guide, follower 20 means on the carriage engaging said guide, said guide extending below the path of normal reciprocation of said follower means and being deflected forwardly from alignment with said path 25 of normal reciprocation and means within the control of the operator for moving the carriage from its path of normal reciprocation downwardly along said guide to a pre-determined loading position, the position of the carriage and hopper being controlled by said guide and said follower means.

9. In a machine for cutting a body of material into relatively small blocks, a carriage, means for reciprocating the same on a pre-determined path of normal reciprocation inclined to the vertical, a hopper on said carriage adapted to the feeding of said body by gravity, forwardly and downwardly transversely to said path, scoring 30 saws and a cut-off saw arranged in cutting relation to the path at the forward end of the hopper, means for turning the hopper to provide intersecting scores, a guide, follower means on the carriage engaging said guide, said guide extending below the path of said follower means in 35 normal reciprocation and being deflected below said path forwardly from alignment with said path of normal reciprocation, and means controlled by the operator for moving said carriage 40 downwardly along said guides to a pre-determined loading position, the position of the carriage and hopper being controlled by said guide and said follower means whereby the hopper is moved substantially to horizontal position for 45 loading.

10. In a machine for cutting a body of material into relatively small blocks, a carriage, means for reciprocating the same on a pre-determined normal inclined path, a hopper on said carriage 50 adapted to feed said body by gravity transversely of said path downwardly and forwardly, scoring saws and a cut-off saw arranged intermediate of said path transverse to each other and substantially parallel to said path, means for turning the carriage near each end of said path providing for the cutting of intersecting scores, said reciprocating means comprising a fluid pressure cylinder having a member reciprocated thereby 55 connected to said carriage whereby the reciprocations of the carriage correspond directly to the reciprocations of said member, means for reversing the operation of said reciprocated member near each end of the normal path of the carriage, means for rocking the carriage operative below 60 said normal path, means actuated at the will of 65

70 75

the operator for controlling the operation of said fluid pressure cylinder and reciprocated member to provide for the movement of the carriage downwardly below its normal path in cooperation with said rocking means to a pre-determined loading position of said hopper.

11. A machine as per claim 10 which is adapted to stand on the floor, said rocking means for the carriage being in the form of a guide and follower means on the carriage engaging said guide, said guide extending below the normal path of said follower means and diverging from said latter normal path to swing the hopper to horizontal position as it moves downwardly below the normal stroke.

12. A machine as per claim 10, the controlling means comprising a removable stop for the carriage to determine the bottom end of the normal stroke and a by-pass valve with suitable connections for connecting the two ends of the cylinder which is of the double-acting type to provide for the passage of the fluid from one end of the cylinder to the other to permit the downward movement below the normal stroke to be performed by gravity.

13. In a machine for cutting a body of material into relatively small blocks, a carriage, means for reciprocating the same on a normal pre-determined path, comprising a pair of cylinders and pistons therein, a piston rod operated by each said cylinder, a crosshead secured to both said piston rods, a guide for said crosshead, a connecting rod connecting the crosshead to the carriage, the cylinders being parallel and spaced apart and the carriage having its path substantially between the cylinders, means for supplying fluid under pressure, connections for leading said fluid under pressure to the cylinder, a hopper rotatably mounted on said carriage on an axis transverse to the path of reciprocation, the hopper being adapted to the feeding of said body in the direction of said axis, scoring saws and a cut-off saw in the path of reciprocation, and means for turning the hopper to form two sets of intersecting scores.

14. In a machine for cutting bodies of material into relatively small blocks, a carriage for said body, a fluid pressure cylinder for reciprocating the same on a normal, substantially upright pre-determined path, scoring saws and cut-off saws in said paths, means for turning the carriage to provide two sets of intersecting scores, the carriage being adapted to the feeding of the body after each cut-off, the said machine having means adapted for control by the operator for controlling the supply of fluid to said fluid pressure cylinder, providing for the downward motion of said carriage to a loading position below said normal path of reciprocation.

15. In a machine for cutting bodies of material into relatively small blocks, a carriage for said body, a fluid pressure cylinder for reciprocating the same on a normal, substantially upright pre-determined path, scoring saws and cut-off saws in said paths, means for turning the carriage to provide two sets of intersecting scores, the carriage being adapted to the feeding of the body after each cut-off, the said machine having means for controlling the fluid pressure cylinder to provide for the motion of the carriage below the normal path of reciprocation, said path being at an angle to the vertical, and means for deflecting said carriage as it moves below the path of reciprocation to bring the hopper to a loading

position with said axis which represents the line of feed substantially horizontal.

16. In a machine for cutting a body of material into relatively small blocks, a carriage, means for reciprocating the carriage providing a forward and return stroke on the same substantially upright normal path, a hopper on said carriage adapted to the automatic feeding of the said body forwardly substantially at right angles to said path, scoring saws and a cut-off saw arranged in cutting relation to said path at the forward end of said hopper, means for turning the hopper to provide for scoring on intersecting lines, means controllable by the operator providing for the movement of said carriage below the lower end of said normal path to loading position.

17. In a machine as per claim 16, having a stop for the carriage at the lower end of the normal path, the same being movably mounted to be displaced by the operator when the carriage is to be moved to loading position and a connection from said stop to the carriage whereby the stop is returned to operative position when the carriage moves upwardly after loading.

18. In a machine for cutting a body of solid material into relatively small blocks, a carriage, means for reciprocating the carriage on a pre-determined substantially upright path, scoring saws and a cut-off saw intermediate of said path, a hopper on the carriage for holding said body and presenting it to the said saws, means for turning the hopper to provide intersecting scores, said reciprocating means comprising a fluid pressure motor of the double action reciprocating type and connections from the motor to the carriage whereby the carriage reciprocates in direct correspondence with the reciprocations of the motor, valve means controlling said motor, means controlled by the turning of the hopper for operating said valve means, reversing the motor at each end of the stroke, and means operative near the end of the down-stroke for relieving the pressure within the fluid pressure motor prior to reversal.

19. In a machine for cutting blocks from a body of solid material, a carriage, means for reciprocating the carriage on a single pre-determined path, comprising a fluid pressure cylinder and a piston therein, scoring saws and a cut-off saw intermediate of said path, a hopper on the carriage for holding the material and presenting it to the saws, the hopper and carriage being adapted to the feeding of the material to the saws and means for determining the rate of feed, means for turning the hopper at each end of said path to provide intersecting scores, a pump for supplying fluid under pressure to said cylinder, a single source of power for said machine in the form of a motor, driving connections from said motor to the pump and connections from the said motor to the scoring saws, cut-off saw, and turning means whereby the carriage is reciprocated and turned and the scoring and cut-off saws are operated from said motor.

20. In a machine for cutting blocks from a body of solid material, a carriage, means for guiding the carriage on a predetermined path, a fluid pressure reciprocating motor and means connecting the carriage to the motor to reciprocate in direct correspondence therewith, scoring saws and a cut-off saw intermediately of said path in operative relation to said path, a hopper on the carriage for holding the material and presenting it to said saws, means for turning the hopper at each end of said path to provide inter-

secting scores, valve means controlling the reciprocations of the motor, means for operating said valve means and means on the carriage, timed by said turning means, for actuating said valve operating means, to move the valve means, substantially at the ends of said strokes, controlling the reciprocations of the motor and carriage, and means for determining the rate of feed of the material to determine the thickness of the blocks.

21. In a machine for cutting blocks from a body of material, a carriage, means for reciprocating the carriage on a pre-determined path, a hopper on said carriage adapted to the feeding of the material transversely to the path of reciprocation, scoring saws and a cut-off saw intermediate of said path projecting into the path of the cake at the forward end of said hopper in the direction of feed, automatic means for turning the hopper at each end of the stroke about an axis parallel to the direction of feed to deter-

mine the angle of scoring, a locking device for locking the hopper after said turning motions and for maintaining it in locked position for the scoring operation, and means for regulating the 5 feeding of the cake to score and cut a predetermined thickness, said locking means comprising positioning means on the carriage for positioning the hopper after each turning motion and a follower-controlled member on the carriage engaging the hopper oppositely to said positioning means, a follower also on the carriage and operatively connected to said member and a track extending along the path of the carriage engaging and controlling the motion of said follower 10 and said member to lock the hopper against said positioning means and hold it locked during the 15 respective strokes of the carriage.
